ABSTRACT OF THE DISCLOSURE

The disclosure of this invention pertains to a jet nozzle for jet propulsion engines, the nozzle having a centre body provided with flaps movable to divert the flow of the gases. Each flap is supported on the centre body by a first and a second link, the first link engaging the flap at a point intermediate between the upstream and downstream ends thereof and being adapted to move the flap away from a stowed position on the body, the second link being adapted to pivot the flap about said point into an obliquely rearward position for thrust-spoiling or an obliquely forward position for thrust-reversing.

This invention relates to a jet nozzle for a jet propulsion engine.

It is known to provide such nozzles with a centre body on which are supported flaps adapted to be moved into the jet stream for the purpose of deflecting the gases from their normal rearward direction. However, in the known arrangements the flaps are pivoted about one extreme end thereof and this results in certain limitations as regards the range through which the flaps can be satisfactorily pivoted.

According to the present invention there is provided in a jet propulsion engine a jet nozzle comprising a centre body and flow-diverting flaps pivoted thereto, characterized in that each flap is pivotally supported at a point intermediate its ends on a mechanism for moving the flaps between a position in which it is flush with a surface wall of the centre body and a position in which at least the medial part of the flap lies spaced from the centre body, and that there is provided means for pivoting the flap, when the latter is in said spaced position, about its pivotal connection to the mechanism between a position in which the upstream end of the flap is contiguous with the centre body and a position in which the downstream end of the flap is contiguous with the centre body.

By virtue of this arrangement it is possible to move the flap into an obliquely rearward or thrust-spoiling position and into an obliquely forward or thrust-reversing position without the need for the large range of pivotal movement which is required if the flap is pivoted about one or other of its ends. Particularly, there arises the advantage of the flap not having to project unduly far from the centre body so that good clearance can be obtained between the flap and the ground during the landing of an aircraft employing such a nozzle in its propulsion plant.

An example of a jet nozzle according to this invention will now be described with reference to the accompanying drawings wherein:

FIGS. 1, 2 and 3 are sectional elevations of the nozzle and show the nozzle in first, second and third operational positions, respectively.

FIG. 4 is a perspective view of the nozzle.

2

The nozzle comprises a main duct 10 divided into two branch ducts 11 by a centre body 12. An exhaust flow from a jet propulsion engine (not shown) to the duct 10 is exhausted to atmosphere through the ducts 11. The ducts 11 are of rectangular cross-section and are each defined by an outer wall 13, a wall 14 of the centre body 12 and two opposite side walls 15. The wall 13 is extended by a retractable panel 16. Normal gas flow through the nozzle has the direction of arrows 17. The mean direction of the normal flow is parallel to the axis, 18, of the duct and is the flow direction required for normal forward propulsion of an aircraft in respect of which the engine and the nozzle are installed.

The centre body is provided in respect of each duct 11 with a flap 19 movable from a first or inoperative position (FIG. 1) into a second or jet spoiling position (FIG. 2) in which the flow has the direction of arrows 20, i.e. obliquely downstream and away from the direction 17. The flap is also movable from the inoperative position into a third or thrust reversing position (FIG. 3) in which the flow has the direction of arrows 21, i.e. obliquely upstream to and away from the direction 17.

In the inoperative position (FIG. 1) the flap 19 is situated in a recess 23 of the centre body 12 and is flush with the wall 14 so as to cooperate therewith in guiding the gas flow over the centre body.

Means for moving the flap from the first to the second position comprise a piston and cylinder fluid pressure motor 24 having a cross head 25 connected by a link 26 to the flap by means of a pivot 27 lying intermediate between the upstream and downstream ends 28 and 29 respectively, of the flap. The flap is supported on the body 12 for arcuate movement about a pivot 30 lying adjacent the end 28 of the flap. The motor 24 is operable to move the cross head 25 from the FIG. 1 into FIG. 2 position and thereby raise the flap about the pivot 30 from the first into the second position. In the latter position a surface 31 of the flap operates to deflect the gas flow into the direction 20.

For the purpose of its movement into the third position the flap is supported on the links 26 for movement about the pivot 27 in the clockwise direction (FIGS. 2, 3) so that in the third position a surface 32, which in the first and second positions is the undersurface of the flap, is presented to the gas flow to divert that flow into the direction 21. It is to be understood that the flap is movable from the second into the third position without that there is a need to return into the first position. Means for so moving the flap comprises a piston and cylinder fluid pressure motor 33 connected between the pivot 30 and a pivot 34 provided on an extension 35 of the flap. In the first and second positions of the flap the motor 33 is in the extended position shown in FIGS. 1, 2. For the purpose of moving the flap from the second into the third position the motor 33 is contracted thereby acting on the extension 35 to turn the flap into the third position.

The connection between the flap and the pivot 30 is constituted by the motor 33, the extension 35 and by a tie link 36 connected between the pivots 30, 26. During movement of the flap between the first and second positions the motor 33 and extension 35 cooperate to keep the flap in a position parallel to the link 36 as if the flap were a part of that link. During movement of the flap between the second and third positions, i.e. the movement about the pivot 27, the links 36, 26 cooperate to retain the pivot 27 in the FIG. 2 position while the motor 33 causes the movement of the flap between the second and third positions and retains the flap in either of those positions.

For the purpose of holding the pivot 27 in the FIG. 2 position, the cross-head 25 is stopped in a position in which failure of the motor 24 would allow the flap to be pushed by the pressure of the gas flow into the first or inoperative position. Also, the flap is so dimensioned that in the second position the gas pressure on the surface 31 tends to tilt the flap in the anti-clockwise direction so that failure of the motor 33 does not result in a change in the angular position of the flap, the motor 33 being at that stage in the fully extended position. However, in the FIG. 3 position the fail-safe requirements are that failure of the motors 33, 24 should not result in a change of the flap away from the third position. This is achieved by operating the motor 24 to move the cross-head 25 into a position in which the motor 24 is at the inner end of its stroke, the link 26 then being at an angle at which failure of the motor 24 would result in that motor being held at the inner end of its stroke. The motor 33 is also at the inner end of its stroke in the third position of the flap, and the flap is so dimensioned that the gas pressure against the surface 32 tends to turn the flap in the clockwise direction whereby failure of the motor 33 would merely result in that motor being held in the condition it occupies.

The flap includes an extension 37 of the surfaces 31, 32, which extension is provided with a bell crank lever 38 connected by a link 39 to the link 36 such that when the flap is moved from the second into the third position the extension 37 is moved from a position of alignment with the surfaces 31, 32 (FIG. 2) into a position forming a bend 40 for the surface 32 to assist in imparting a further reverse component to the gas flow.

Although it is preferred to move the flap into the third position by first moving it into the second position, it is possible to operate the motors 24, 33 simultaneously so as to move the flap way from the recess 23 at an attitude in which the flap is at first substantially parallel with the axis 18 and is then gradually turned into the third position as the necessary clearance between the pivot 27 and the body 12 increases.

An important consideration in the construction of the nozzle is that, in order to move the flap from the first into the second or jet spoiling position, it should not be necessary to pass first through the third or thrust reversing position. This requirement arises because it would be undesirable to have to attain the position of neutralizing the momentum of the jet (this being substantially the effect of the flaps in the second position) by first subjecting the aircraft to the braking effect produced in the third position of the flap. It will be seen that this condition is satisfied.

It is a further important consideration in the construction of the nozzle that the flap should not at any time project unduly far from the centre body 12. This is particularly required in aircraft where there is a relatively small clearance between the nozzle and the ground during landing. In this connection, it may be desired to have the flaps in the second position during the landing approach and to move the flaps into the third position immediately on touch down. In an aircraft which has rear-mounted engines and which touches down at a relatively high angle of incidence, as exemplified by a line 41 signifying the relative position of ground level on touch down, the ground clearance of the nozzle may be relatively small, and it is important to be able to operate the flaps without the danger of the lower one of the flaps fouling the ground. The clearance between the lower flap and the ground is shown at 42 (FIG. 2) and 43 (FIG. 3). It will be seen that by having the facility of pivoting the flap about the pivot 27 this clearance problem is reduced to manageable proportions.

The motor 24 and the links 26, 36 may be seen as a means, not only for lifting the flap from the first into the second position, but also as a means for so disposing

the pivot 27 that the flap can be moved between the second and third position with a minimum of angular displacement. It is clear that if the flap were moved from the second into the third position by continuing anti-clockwise movement of the flap from the first into the second position, the ground clearance of the lower flap would be very substantially reduced.

Referring to the panels 16, when these panels are retracted (FIGS. 2, 3) the ducts 11 have a convergent configuration as determined by the walls 13 and the upstream part of the centre body. The narrowest part of throat of the ducts 11 is indicated by a line 44. When the panels 16 are extended (FIG. 1) the ducts 11 include the downstream part of the centre body and thus have a convergent-divergent configuration. With the flaps 19 in their first or inoperative position, it is immaterial whether the panels 16 are retracted or extended, but if the flaps 19 are to be moved into the second or third position the panels 16 must of course be retracted to provide the necessary opening for the efflux of the gases. In other words the flaps 19 are provided in a position downstream of the throat 44 and if the nozzle has a wall part, such as that formed by the panels 16 when extended, lying downstream of the throat in a position which would impede the efflux of the diverted gases, then it is necessary for that wall part to be removable to make possible such efflux.

FIG. 4 shows two nozzles situated side by side in operation below the trailing edge of the wings 45 of an aircraft. In one of the nozzles the flaps 19 are in the thrust reversing position and the panels 16 are retracted while in the other nozzle the flaps 19 are in the first or inoperative position and the panels 16 are extended.

Referring to the second position of the flaps 19, although the illustrated example shows the flaps in an oblique position in relation to the axis 18, it is possible to arrange for the flaps to be moved into a position approximately at right angles to the axis 18 so as to constitute not only a jet spoiler but also act as an air brake. However, this would be done only inasmuch as considerations of ground clearance permit.

What we claim is:

1. In a jet propulsion engine, a jet nozzle comprising a centre body and flow-diverting flaps pivoted thereto, characterized in that each flap is pivotally supported at a point intermediate between its ends on a mechanism for moving the flap between a position in which it is flush with a surface wall of the centre body and a position in which at least the medial part of the flap lies spaced from the centre body, and that there is provided means for pivoting the flaps, when the latter is in said spaced position, about its pivotal connection to the mechanism between a position in which the upstream end of the flap is contiguous with the centre body and a position in which the downstream end of the flap is contiguous with the centre body.

2. Nozzle according to claim 1, wherein said mechanism includes a link pivotally connected between said intermediate point and a point on the centre body and co-operating to support the flap from movement between said flush and spaced positions, and wherein said means include a fluid pressure motor pivotally connected between the flap and said point on the centre body so as to participate in movement of the mechanism.

3. Nozzle according to claim 1, the flap including at the upstream end thereof a flow-diverting extension pivoted to the flap for movement between a position of alignment with the plane of the flap and a position at an angle to said plane so that when the flap during the operation thereof is in the position wherein its downstream end is contiguous with the centre body the extension points in the upstream direction to further divert gases already diverted by the flap itself, and wherein means

3,570,247

5

are provided for moving the extension between said two
positions thereof.
